MUSICAL TOY FIGURE

Nicholas T. Baldanza, Rutherford, N.J., assignor to William Kratt, Union, N.J.

Application January 27, 1959, Serial No. 54,331

Term of patent 14 years

(Cl. D34—15)

FIG. 5

FIG. 1

FIG. 3

FIG. 2

FIG. 4

Fig. 1 is a front elevational view of a musical toy figure showing my new design;

Fig. 2 is a rear elevational view thereof;

Fig. 3 is a side elevational view thereof looking at the right side of Fig. 1;

Fig. 4 is a side elevational view thereof looking at the left side of Fig. 1; and

Fig. 5 is a top plan view thereof.

I claim:

The ornamental design for a musical toy figure, substantially as shown.
